UNITED STATES PATENT OFFICE.

WILLIAM H. MASON, OF EASTON, PENNSYLVANIA.

PORTABLE ELECTRICAL GENERATING APPARATUS.

1,308,959.

Specification of Letters Patent.

Patented July 8, 1919.

Application filed December 15, 1914. Serial No. 877,317.

To all whom it may concern:

Be it known that I, WILLIAM H. MASON, a citizen of the United States, and a resident of Easton, county of Northampton, and 5 State of Pennsylvania, have invented certain new and useful Improvements in Portable Electrical Generating Apparatus, of which the following is a specification.

My invention relates to portable apparatus 10 for generating electrical current, and while it may be used for any purpose, the embodiment thereof described herein is particularly designed for use in generating current for detonating explosives in blasting 15 operations.

In the so-called "blasting machines" or "push down batteries" in common use for this purpose, reliance is had upon a manually operated push rod and rack and gear 20 connections for getting the generator up to a speed at which the apparatus is expected to furnish sufficient current for igniting the blasting charge by means of fusees. These blasting machines or push down batteries being 25 manually operated are uncertain and unsatisfactory in their operation, the current produced cannot be certainly known in advance, and frequently unexploded charges are left in the quarry, creating an extremely 30 dangerous condition, and furthermore the number of charges which can be detonated at one time by such manually operated devices is quite limited.

According to universal practice there is 35 always available, wherever mining or quarrying and blasting is going on, a source of fluid pressure either in the form of compressed air or steam, and frequently both. Apparatus in accordance with the present 40 invention is designed to be operated by such fluid pressure, and either by steam or compressed air, as may be most convenient, and it therefore requires no source of power other than is conveniently available and must be 45 provided for drilling purposes.

Among the objects of the present invention are the provision of a light, portable, compact apparatus which will stand severe handling such as it is subjected to in quarries and mines and which can be operated 50 efficiently from a source of fluid pressure as steam or compressed air.

A further object of the invention consists in the construction of the motor in such manner that the generator is protected in the

operation of the motor from the access of steam thereto which, if not prevented, might result in injury to the generator.

A further object of the invention consists in the provision of means for mounting the 60 fluid pressure motor direct on the generator casing, thus making it possible to mount the rotor for the motor direct on the generator shaft, eliminating compensating connections, as universal joints and the like, and thus 65 materially cutting down the weight of the apparatus, which is important in a portable apparatus in which weight must be reduced to the minimum.

A further object of the invention consists 70 in the provision of positive indicating means by which the operator will be positively informed when sufficient current is being generated for the purpose to which the apparatus is to be put, eliminating all uncertainty 75 from this source, and insuring, for example, the generation of sufficient current to detonate all the fusees which may be connected therewith for blasting purposes.

The invention further resides in the improvement of apparatus of the kind described in numerous important respects, and with the foregoing and related objects in view, my invention consists in the apparatus parts, improvements and combinations herein set forth and claimed.

In the accompanying drawings forming a part of this specification, and wherein the same reference numerals are used to designate the same parts throughout, I have 90 shown, for the purpose of illustration only, and in order that my invention may be clearly understood, one form of apparatus in which my invention may be embodied, and in the said drawings Figure 1 is a view 95 partly in perspective and partly in cross-section illustrating the use of my improved apparatus arranged for the purpose of detonating blasting charges. Fig. 2 is a front view of the apparatus, the forward side of 100 the box or casing in which the same is contained being removed to show the interior, and the lid being shown in dotted lines. Fig. 3 is a fragmentary plan view showing one form of switch and wiring connections. 105 Fig. 4 is a view showing a mode of connecting the motor to the generator casing, the motor being shown in central vertical cross-section. Fig. 5 is a face view of the motor with the cover plate removed, certain parts 110

thereof being shown in cross-section, and Fig. 6 is a fragmentary horizontal section taken on the line 6—6, Fig. 5 and further illustrating one manner of connecting the 5 motor to the generator casing.

Reference numeral 10 designates the box or casing in which the apparatus is preferably installed and preferably having a hinged lid or cover 11 provided with a 10 carrying handle 12. Such cover is a convenience for protecting the switch and other parts and for permitting the apparatus to be closed and locked, but it will be readily understood that such cover may be dispensed 15 with if desired and the carrying handle placed directly on the inclosing box or container. The generator 13 is preferably secured to the base of the box or container 10 in any convenient manner, as by being 20 bolted thereto, as shown, and the motor 14, which is preferably of the turbine type, is secured to the generator casing and is provided with a pipe 15, the end of which is exposed for conveniently coupling the same 25 to a pipe as 16 for supplying fluid under pressure which, as already stated, is available either in the form of steam or compressed air wherever blasting operations are being carried on.

30 A preferable manner of connecting the motor to the generator casing consists in the provision of the motor casing with lugs 16^a provided with interiorly threaded openings, whereby it may be secured to the generator 35 casing. Any form of generator may be used. In one form of generator commonly on the market threaded rods 17 project from the generator casing and are normally provided with nuts for holding the parts of the 40 generator casing together. With a generator so constructed the threaded rods or bolts 17 may be screwed directly into the threaded openings in the lugs 16. While this is a convenient form of connection, it will be 45 understood that other modes of directly connecting the motor to the generator casing may be resorted to if desired. The rotor 18 of the motor 14 is preferably of nonmagnetic material so as not to interfere with the 50 operation of the generator and is preferably connected directly to the shaft 19 of the generator, as by means of set screws 20, and is provided with the customary buckets 21 upon its periphery and the fluid under pressure is 55 supplied thereto by a nozzle or nozzles conveniently situated. In the form shown there are two nozzles 22, one at each of the opposite sides of the motor casing, connected by a pipe 23 and supplied from the pipe 15. 60 The bores for nozzles 22 may be conveniently closed by plugs, 24, 24. A cover plate 25 is secured to the member 26 of the motor casing as by means of bolts 27, and the cover plate 25 has the exhaust opening 28 formed 65 therein, such opening being preferably

formed on the lower side of the motor casing to permit the escape of water therefrom, as when steam is used as the motive fluid.

With a light apparatus of this kind, in which friction must be reduced to a minimum, it is not practical to provide a tight or packed joint where the shaft 19 passes through the member 26 of the motor casing, and it is therefore necessary to allow a certain amount of clearance where such shaft 70 passes through the opening 29 leading into the motor casing. Unless such provision is made to prevent it, the motive fluid will escape through the opening 29 to a considerable extent, and when steam is used as the 75 motive fluid, its escape through this opening, if not prevented, will injure and ultimately ruin the generator, and furthermore the other parts within the casing will be injured by the presence of steam within the box or 80 container in which the apparatus is placed. I therefore make provision for preventing this undesirable action from taking place. In the form of apparatus shown this result is secured by placing the spokes 29^a of the 85 rotor at an incline, thus making up substantially a fan structure, which creates a pressure within the motor casing toward the exhaust side and substantially sucks away the fluid within the motor casing from the 90 side thereof next to the generator, so that, instead of motive fluid being discharged through the opening 29, air is drawn to some extent through said opening into the 95 motor casing, thus preventing the discharge of fluid, as steam, against the generator and within the container for the apparatus, and drawing fresh air into such container, which passes into the motor casing through the opening 29 and out with the exhaust. The 100 same action of course occurs when compressed air is used as the motive fluid, except that in this case it is not so important, although it does assist to an extent in keeping the apparatus cool. 105

The box 10 is preferably provided with a top plate 30 through which the pipe 15 passes and upon which the controlling switch 31 is preferably mounted. The lead wires 32, 32 from the generator are connected to 110 the pivots of the switch 31. The wires 33, 33 from one branch of the switch run to a voltage indicator which may conveniently take the form of a lamp 34 and which may be conveniently mounted within the 115 box or casing 10. A window 35 placed near the lamp 34 affords a convenient means to the operator for observing the lamp or other voltage indicator. The wires 36, 36 from the 120 opposite branch of the switch run to binding screws 37, 37 to which the outside circuit is connected, and wires 38, 38 from said binding screws which may be conveniently attached as by means of thumb-screws 39 125 form the outside circuit. These wires 38, 38 130

may be connected in series, as shown in Fig. 1, to the wires from the fusees 40, 40, placed within the explosive, as powder, dynamite or the like 41 in the hole 42. But one such hole is shown in the drawings and but two fusees, but, as will be understood, the number of such holes, and the number of the fusees in any charge may be increased substantially indefinitely, it being readily possible for a small apparatus constructed in accordance with my invention and weighing in the neighborhood of 35 or 40 pounds to generate a current which will detonate as many as 250 fusees at one time, and the same may be distributed throughout the charges to be detonated in such manner as to secure the best results.

In the operation of the device for blasting connection is made through the pipe 15 to a source of fluid pressure, as compressed air or steam, which is conveniently available, and the throttle 43 may be opened to such extent as to operate the apparatus at the proper speed, and it will be apparent to the observer when the correct speed has been reached by the fact that the lamp 34 is burning brightly the switch connections having been made so that the current is passed through the lamp, and a lamp of proper voltage being selected, as will be understood. When the lamp is burning brightly it is only necessary to quickly shift the switch 31 so as to throw the outside wires 38 into the circuit, whereupon the current will be passed through the fusees and the charges detonated, the current being automatically broken by the explosion which, of course, ruptures the outside current by tearing the wires apart.

When desired, a lamp or lamps can be substituted for the fusees in the outer circuit and the apparatus used for generating current for lighting the lamp or lamps. This is an extremely convenient arrangement in blasting operations, as it frequently becomes necessary to inspect the interior of the holes being drilled, as for determining when crevices are present, and for lighting up the interior of the holes when fishing for lost drills or the like. Of course the lamps when placed in the outer circuit may be used for illuminating purposes of any sort.

While I have described and illustrated a specific form of apparatus, it is to be under-

stood that the same is shown and described for the purpose only of affording a clear understanding of my invention, and that my invention is not limited thereto, but that departures from and changes in the form of apparatus shown may be made, within the scope of my claims, without departing from my invention or sacrificing any of the advantages thereof.

Having thus described my invention, I claim:

1. A portable apparatus for detonating blasts comprising in a single unit a rotary electrical generator, a fluid pressure motor for imparting continuous rotary movement to said generator, means for detachably connecting the motor with a source of fluid under pressure to drive same, an indicator circuit, a current passage indicator in said circuit, means for attaching an external circuit containing fuses for detonation of blasting charges, and a two position switch adapted in one position to connect the generator with the indicating circuit, and in the other position to connect the generator with the external blasting circuit, substantially as shown and described.

2. A portable motor and generator outfit comprising a box, a generator therein, a motor on the generator casing and having its exhaust directed out the side of the box, a lamp in said box, a window in the side of the box adjacent to said lamp, and a switch for passing the motor current at will through said lamp or through an outside circuit, substantially as set forth.

3. A portable apparatus of the class described comprising a box, an electrical generator therein, a fluid pressure motor connected to said generator and having its exhaust passage extending through the side of the box, a top member for the box, a lamp in said box, a switch on said top member for passing the current at will through said lamp or through an outside circuit, and a cover for the box, substantially as set forth.

In testimony that I claim the foregoing I hereunto set my hand this 10th day of December, 1914.

WILLIAM H. MASON.
